Inventor
Alexander Andrews,
by *A. Andrews*
Attorney

UNITED STATES PATENT OFFICE.

ALEXANDER ANDREWS, OF CARBONDALE, ILLINOIS.

FLUID-PRESSURE REGULATOR.

No. 821,574.

Specification of Letters Patent.

Patented May 22, 1906.

Application filed August 8, 1905. Serial No. 272,564.

To all whom it may concern:

Be it known that I, ALEXANDER ANDREWS, a citizen of the United States, residing at Carbondale, in the county of Jackson and State of Illinois, have invented certain new and useful Improvements in Fluid-Pressure Regulators; and I do declare the following to be a full, clear, and exact description of the invention, such as will enable others skilled in the art to which it appertains to make and use the same.

This invention relates to fluid-pressure regulators; and one of the principal objects of the same is to provide a device of comparatively simple construction which can be quickly adjusted to any required pressure desired within the scope of the pressure of the main.

Another object is to provide means whereby the pressure when once adjusted may be automatically regulated by means of a weight.

These and other objects are attained by means of the construction illustrated in the accompanying drawings, in which—

Figure 1 is a side elevation of a fluid-pressure regulator made in accordance with my invention. Fig. 2 is a central vertical section of the same. Fig. 3 is a perspective 30 view of one of the cup-shaped leather valves. Fig. 4 is a central vertical section of the perforated inner cylinder, and Fig. 5 is a perspective view of the holder for the small cup-shaped leather valves for said inner cylinder.

Referring to the drawings for a more particular description of my invention, the numeral 1 designates the outer casing or casting, provided with an inlet-opening 2 and an outlet-opening 3. Projecting from the casing 40 are a pair of spaced bearing-lugs 4, to which a lever 5 is pivoted at 6, said lever being connected to a piston 7 by a pin or screw 8. Above the cylinder or casing 1 is a tubular cylinder 9, threaded, as at 10, and connected 45 to the casting 1, as shown in Fig. 2. The piston 7 has connected at its upper end a cup-shaped flange 11, and supported by said flange is a leather washer 12, which is of substantially cup shape, and fitted within said 50 washer is a disk 13, nuts 14 and 15 serving to clamp the flange, the washer, and the cup-

shaped leather valve in place. This valve is adapted to slide within the cylinder 9. At the lower end of the piston a valve-holder 16 is connected by a projecting threaded portion 17 to the piston, and at opposite ends this valve-holder supports two oppositely-disposed cup-shaped leather valves 18, said valves adapted to reciprocate within the inner cylinder 19, said cylinder 19 being provided with series of perforations 20, as shown in Fig. 4. A weight 21 is fitted to slide upon the lever 5 and is adapted to be adjusted at such position upon said lever as to regulate the flow of water through the outlet at the degree of pressure desired.

From the foregoing it will be obvious that my invention is of comparatively simple construction, is reliable and efficient in use, and can be quickly fitted and adjusted to the required degree of pressure.

Various changes in the form, proportion, and the minor details of construction may be resorted to without departing from the principle or sacrificing any of the advantages of this invention.

Having thus described my invention, what I claim as new, and desire to secure by Letters Patent, is—

A fluid-pressure regulator comprising an outer cylinder 9, a casing 1 secured to said cylinder and provided with inlet and outlet openings, an inner perforated cylinder 19 secured within the casing 1, a piston provided with a large cup-shaped valve 12 seated upon a cup-shaped flange 11 for operating in the main cylinder, a spool-shaped valve-holder 16, a pair of oppositely-disposed cup-shaped valves 18, secured at the ends of said holder by screws 17, and adapted to slide in the perforated cylinder 19, a lever pivoted to the casing and connected to the piston, and a weight adjustable upon the lever, substantially as described.

In testimony whereof I have hereunto set my hand in presence of two subscribing witnesses.

ALEXANDER ANDREWS.
